UNITED STATES PATENT OFFICE

146,382

DESIGN FOR A COMBINED FRUIT JUICER
AND GRATER HEAD

Edward Prinz, St. Paul, Minn.

Application September 10, 1945, Serial No. 121,968

Term of patent 14 years

(Cl. D89—1)

To all whom it may concern:

Be it known that I, Edward Prinz, a citizen of the United States and residing at St. Paul, in the county of Hennepin and State of Minnesota, have invented a new, original, and ornamental Design for Combined Fruit Juicer and Grater Head, of which the following is a specification, reference being had to the accompanying drawing, forming part thereof.

I claim:

The ornamental design for a combined fruit juicer and grater head, as shown.

EDWARD PRINZ.
